US00D996603S

(12) **United States Design Patent** (10) **Patent No.:** **US D996,603 S**
(45) **Date of Patent:** **** Aug. 22, 2023**

(54) **HICCUP RELIEVING APPARATUS**

(71) Applicants: **Victor W. Fehlberg**, Longmont, CO (US); **Ali Seifi**, San Antonio, TX (US)

(72) Inventors: **Victor W. Fehlberg**, Longmont, CO (US); **Ali Seifi**, San Antonio, TX (US)

(73) Assignee: **Higher Innovations, Inc.**, Longmont, CO (US)

(**) Term: **15 Years**

(21) Appl. No.: **29/822,601**

(22) Filed: **Jan. 11, 2022**

(57) **CLAIM**

The ornamental design for a hiccup relieving apparatus, as shown and described.

DESCRIPTION

FIG. 1 is a perspective view of the hiccup relieving apparatus showing our new design with the bottom cap removed. FIG. 2 is a perspective view of the hiccup relieving apparatus showing our new design with the bottom cap in place. FIG. 3 is a left side view thereof.

FIG. 4 is a right side view thereof.

FIG. 5 is a back view thereof.

FIG. 6 is a front view thereof.

FIG. 7 is a top view thereof; and,

FIG. 8 is a bottom view thereof.

The broken lines in the drawings depict portions of the hiccup relieving apparatus that form no part of the claimed design.

1 Claim, 2 Drawing Sheets
